UNITED STATES PATENT OFFICE.

RAYMOND M. HOOE, OF EVANSVILLE, INDIANA.

LUBRICATING SYSTEM.

Application filed March 25, 1922. Serial No. 546,772.

To all whom it may concern:

Be it known that I, RAYMOND M. HOOE, a citizen of the United States, residing at Evansville, in the county of Vanderburg and State of Indiana, have invented certain new and useful Improvements in Lubricating Systems, of which the following is a specification, reference being had to the accompanying drawings.

10 It is the purpose of the present invention to provide a lubricating system for engines, especially of the stationary type, and wherein a suitable tank is included, for the reception of the lubricant, there being filtering means in the tank, for the purpose of filtering the lubricant, as it flows through the system of piping.

Another purpose is the provision of a lubricating system embodying an arrangement of pipes, sight feed drip valves, cups and wiper cups for feeding the lubricant from the pipes, to various parts of the engine, for instance to the eccentrics, bearings, cross head and the like.

25 A still further purpose is the provision of a system with which old oil can be used more than once, due to the fact that the oil passes through a filtering device contained within the tank, and through which the oil 30 percolates, and then feeds by gravity through the system of pipes.

While the design and construction at present illustrated and set forth are deemed preferable, it is obvious that as a result of 35 a reduction of the invention to a more practical form for commercial purposes, the invention may be susceptible of changes, and the right to these changes is claimed, provided they are comprehended within the 40 scope of what is claimed.

The invention comprises further features and combination of parts, as will be herein-after set forth, shown in the drawings and claimed.

45 In the drawings:—

Figure 1 is a view in elevation of an engine, of a stationary type, in connection with which an improved lubricating system is used;

50 Figure 2 is an end elevation of the engine, also showing the lubricating system, illustrating the tank in section, in order to illustrate the filtering means for the lubricant;

55 Figure 3 is an enlarged detail sectional view of one of the regulating sight feed drip valves;

Figure 4 is a detail view of the wiping cup, which feeds the lubricant to the cross head;

Figure 5 is a detail view of means for feeding lubricant to the cap 25;

Figure 6 is a detail sectional view through one of the wiping cups of a cross head and one of the perforated feed cups, showing how the wiping cups wipe the lubricant from the perforated feed cups; and

Figure 7 is an enlarged detail view of one of the wiping cups to be carried by the eccentrics.

Referring to the drawings, 1 designates a base of a conventional form of engine, especially of the stationary type, and rising from the base of the engine are supports 2, which support the container or tank 3, in which the lubricant is contained. Carried by the side of the tank and communicating therewith is the usual form of gauge glass 4, for disclosing the quantity of lubricant in the tank.

Extending from the bottom of the tank 30 and communicating therewith is a globe valve 6. Extending from the globe valve casing laterally in opposite directions are pipes 7 and 8 and extending from a T 7^b at the end of the pipe 7 are pipes 7^a and 8^a. 85 Extending downwardly from the T 7^b is a pipe 9. The pipe 7^a is provided with sight feed drip valves 10, which have regulating valve stems 11, for regulating the lubricant which flows from the nozzles 12 of said valves, into the cups 13. These cups are carried by the tubes or pipes 14, which supply the eccentrics 15 of the engine with lubricant. The pipe 9 also carries a sight feed drip valve 16, through which the lubricant may be regulated by means of the valve stem 17, for the purpose of feeding the lubricant to the main bearing 18 of the engine. The outer end of the pipe 8^a also carries a sight feed drip valve 19, including 100 the stem 20 for regulating the lubricant through the pipe 21. This pipe connects with an elbow 22, which is mounted upon the support 23. A short pipe or nipple 24 axially aligned with the shaft 26 bearing the drive wheel 31 is engaged in the elbow 22 and in turn is rotatably engaged by a cap 25 which is thus supported for rotation in a plane paralleling the plane of rotation of the drive wheel 31. The eccentric or pitman pin 30 of the drive wheel is provided with a central port 23 by means of which

lubricant may be fed to the rod R and which rod communicates with a short nipple 29 mounted axially of the pin 30. With the outer end of this pin a second cap 28 is rotatably engaged and the caps 25 and 28 are connected by a conduit 29 so that the supply of lubricant may pass from the pipe 21 to the pin 30. For instance when the drive wheel is rotating, the radial pipe 27 during every revolution extends downwardly, therefore an intermittent feed of lubricant is permitted to flow to and through the elbow 28, for the purpose of keeping the pin 30 well lubricated, to enable the pitman to have freedom of movement during the operations of the engine.

The lubricating pipe system also includes a pipe 34^a branching from and communicating with a pipe 8. This pipe 34^a is connected to a feed drip valve 37, downwardly from which a pipe 34 extends. The lower end of the pipe 34 terminates in a lubricating cup 38, the bottom of which is provided with perforations 39. The interior of the cup 38 is packed with suitable gauze, such as fabric and metal wool as indicated at 40, there being a wire gauze 41 above the packing to hold the packing in place. The lubricant passes down through the pipe 34 and is filtered through the packing and passes out through the perforations 39. Rising from the cross head 42 is a wiping feed cup 43, in the upper portion of which a felt wick 44 is secured in the groove 45. The wiping feed cup 43 is positioned, so that as the cross head reciprocates, the wick 44 will wipe against the perforated bottom of the pipe 38. The wick 44 acts to carry the lubricant through the passage 46 of the cross head, for lubricating the connecting pin, which connects the piston rod and the pitman. Connected to the pipe 34 and extending laterally and downwardly are branch pipes 47 terminating in nozzles 48, which convey the lubricant into the feed cups 49, which are mounted upon the upper walls of the cross head guideways of the engine. By means of the cups 49 lubricant is conveyed to the guideways in which the cross head reciprocates. Extending from the drip feed valve 37 is a pipe 50 which terminates in a drip feed valve 51, which conveys lubricant to the piston valve casing 52.

Arranged in the tank 3 is a filterer 53, the base 54 of which rests upon the bottom of the tank. The base 54 is of larger diameter

than the upper part of the filterer, therefore an annular space 55 is caused to be formed between the wall of the filterer and the wall of the tank and into which the lubricant rises through the openings 56 in the upper wall of the base. Supported by the bottom of the filterer is suitable filtering material proper, 57 which comprises a mixture of fabric and metal wool 58 held between several upper and lower layers of a wire fabric or gauze 59 and 60. The marginal upper portion of the wall of the filterer terminates in a flange extending toward and in engagement with the marginal portion of the wall of the tank, for the purpose of preventing the lubricant from running over the upper edge of the walls of the filterer and the tank. It is obvious that the filterer may be removed at any time, for the purpose of cleaning the same.

The invention having been set forth, what is claimed is:—

1. In a lubricating system for engines, an oil reservoir, a system of piping having a single pipe connection with said reservoir and including a pipe provided with a movable connection with the shaft of the drive wheel, said pipe being in turn connected to the crank pin of the drive wheel, whereby upon every revolution of the drive wheel, lubricant may be fed through the pipe to the crank pin.

2. In a lubricating system, the combination with a pipe operatively connected with a drive shaft of an engine, and being in turn operatively connected to the eccentric pin of the drive wheel which is mounted upon said shaft, whereby when the pipe assumes a position below the drive shaft, lubricant may pass therethrough and feed to the eccentric pin, and means for feeding lubricant to the pipe.

3. In a lubricating system for the purpose indicated, the combination with a lubricant supply, piping operatively connected to said supply and terminating in a feed cup having a perforated bottom, a filling of filtering material within the cup, a movable member, a wiping cup including a wiping wick to wipe against the perforated surface of the feed cup, whereby lubricant may be conveyed to the movable member, during its reciprocating movements.

In testimony whereof I hereunto affix my signature.

RAYMOND M. HOOE
